TYPEWRITING MACHINE

Henry A. Avery, Groton, and Charles Walker,
Syracuse, N. Y., assignors to L. C. Smith &
Corona Typewriters, Inc., Syracuse, N. Y., a
corporation of New York

Application October 30, 1942, Serial No. 463,962

8 Claims. (Cl. 197—17)

The invention relates to improvements in typewriting machines, and, more particularly, in the type bar actions of such machines.

The principal objects of the invention are to provide an efficient and compact key-controlled power-actuated type bar action for typewriting machines; to provide simple, easily operated, and efficient means for varying at will the impression force of the types; to provide an improved type bar action in which the power actuated types print by momentum accumulated by the type bars during their printing strokes and are rapidly returned, all with a minimum of noise; and to improve type bar actions of the kind disclosed in United States patents to Mansfield C. Crawley, Reissue No. 15,640, No. 1,455,112 and No. 1,503,033 and adapt the same for embodiment in compact form in a type bar case-shifting or type bar segment case-shifting machine of the kind disclosed in United States patents to Gabrielson numbered 1,018,968; 1,467,723; 983,490; 1,032,131 and 2,028,200.

Other objects and advantages of the invention will appear from the following description in connection with the accompanying drawings illustrating the preferred embodiment of the invention.

In the drawings:

Figure 1 is a fragmentary side view of the machine with parts broken away.

Figure 2 is a detail top plan view of the type bar actuator retracting means with certain parts broken away.

Figure 3 is a view similar to Figure 1 illustrating the typing action of a type bar.

Figure 4 is a fragmentary top plan view of a part of the mechanism, certain parts being shown in section and others broken away.

Figure 5 is a fragmentary rear elevation of parts of the mechanism, certain parts being broken away.

The improved power-actuated type bar action is shown as embodied in the known L. C. Smith typewriting machine, and only so much of the machine as is necessary to an understanding of the present invention is shown and will be particularly described.

The system of type bar actions and the actuating means therefor are mounted in a suitable stationary main framework of the machine, portions of which shown are designated 10 and certain parts of which are hereinafter specifically referred to. The usual roller platen 11 is mounted in the usual platen carriage 12 which, in turn, is mounted on the main framework as usual to

travel transversely of the machine for letter feeding or spacing under control of a suitable escape-
ment mechanism, not shown.

The type bars 13 (only two of which are shown) 5 of the usual arcuate system of type bars have their pivots 14 located in an arc lying in an up-
wardly and rearwardly inclined plane, said pivots being carried by the usual type bar support or segment 15. The effective types strike on the 10 upper front portion of the platen, each type bar carrying a lower case type 16 and an upper case type 17, and the type bar segment being shift-
able by suitable case shift means, not shown, downward substantially in the oblique plane in 15 which it lies to condition the machine for upper case typing. The segment is preferably sup-
ported as shown in United States Patent No. 2,028,200 to Gabrielson, for such case shifting movement. The type bars are normally sup-
ported adjacent their forward ends by the usual obliquely disposed arcuate type bar rest 18 which is supported by means, not shown, to shift with 20 segment 15.

Each type bar has pivoted thereto at 19 above 25 and forward of its pivot 14 the forward end of a different one of a series of rigid draw links 20 the rear ends of which are pivoted at 21 to the upper ends of a series of sub-levers 22, the links 20 being all of the same length and adapted to 30 swing about their pivots 21 during case shifting of the system of type bars. The pivots 19 and the pivots 21 respectively lie in obliquely disposed arcs which are concentric with and disposed in planes parallel to that of the type bar segment 35 and the series of type bar pivots 14 so that, when the segment is case shifted, the links 20 will hinge about pivots 21 as is common in segment shift machines.

The several sub-levers 22 (only a few of which 40 are shown) are pivoted in slots in a segment 94 fixedly held to framework 10 and have their pivotal axes 23 located in an arc which is of greater radius than that of the series of pivots 21 and is disposed in a vertical plane transversely 45 of the machine. The lower arms of the levers 22 are so shaped as to normally register or be arranged in a straight row extending transverse-
ly of the machine and each such lever is formed forward of its lower arm with a finger 22a per-
manently bendable or adjustable fore and aft 50 of the machine, the levers being formed of sheet metal adapted for formation of permanent bends therein. These fingers are adapted to engage the upper portions of cushioning and type bar 55 repulsing leaf springs 24 before the type bars

reach printing position on their printing strokes, said springs being arranged in a straight row transversely of the machine forward of the fingers 22^a and being secured at their lower ends to a part of the stationary framework 10 of the machine. The construction is such that each lever 22 has two arms of substantially equal effective length.

Each lever 22 has pivotally connected thereto at 25 the forward end of a different one of a series of rearwardly extending couplers 26, the couplers being arranged in a straight horizontal row across the machine with their pivots in axial register for selective swinging of the couplers up and down about a straight horizontal axial line extending transversely of the machine. Above and to the rear of their pivots the couplers have connected thereto the forward ends of a row of type bar and coupler return springs 27 anchored at their rear ends to a part of the stationary framework 10. These springs normally yieldingly hold the type bars against type bar rest 18 and the couplers against a horizontal coupler rest 28. The couplers in rear of rest 28 extend through and are guided in vertical slots in a coupler guide comb 29 which extends horizontally across the machine, said coupler rest and coupler guide comb being mounted on a part of the stationary framework 10. The rear edge of the coupler rest is undercut as shown at 28^a, and each coupler is formed with a forwardly facing and forwardly and downwardly inclined shoulder 30 normally spaced slightly rearward of the undercut rear edge of the coupler rest to permit upward swinging of the coupler about its pivot 25 but engageable with said undercut edge to lock the connected type bar against any appreciable rebound from type bar rest 18. Each coupler 26 is formed with a rearwardly facing shoulder 31 which is slightly undercut at its upper end and is normally located rearward of comb 29 and, at the lower edge of each coupler, the coupler is formed with a rearwardly extending finger 32, the upper edge of which extends rearward from the lower end of shoulder 31.

A universal type bar actuator 33, comprising a straight bar extending horizontally across the machine and formed at its ends with pendent side arms, has the lower ends of its side arms fixed to a horizontal rock shaft 34 which, in turn, extends horizontally across the machine and is journaled at its ends at 35 on the main framework 10. The cross bar of the actuator normally overlies and is spaced above all of the coupler fingers 32, and the straight forward edge of the actuator cross bar is normally located above and slightly to the rear of the upper ends of coupler shoulders 31.

The actuator 33 is rockable forwardly from its normal position to actuate a selected type bar by means of two constantly tensioned pull springs 36 connected at their rear ends to lugs 37 on the side arms of the actuator and extending forwardly and downwardly therefrom with their forward ends anchored to the lower ends of a pair of rock arms 38 pendent from and fixed to a rock shaft 39 adjacent opposite sides of the machine. Rock shaft 39 extends horizontally transversely of the machine at the rear of the keyboard and is journaled at its ends at 40 on the main framework 10. Adjacent the right hand side of the machine, the shaft 39 has fixed thereto, and preferably formed integrally with the adjacent arm 38, a rearwardly extending rock arm 41 having journaled thereon at its rear end a small roller 42

42 engaged in one or the other of a plurality of latching notches 43 in the eccentric periphery of a conversely rotative plate cam 44. Cam 44 is fixed on a short horizontal shaft 45 journaled in the framework 10 and extends transversely of the machine above roller 42. The cam may be rotated to engage different ones of its notches 43 with roller 42, a handle 46 being for this purpose fixed to the outer or right hand end of the shaft 45 where it is accessible to the typist from the exterior of the machine. Stop fingers 47 and 48 on the cam are engageable with roller 42 to limit maximum rotation of the cam. By engaging the roller 42 in different notches in cam 44, the normal tension of the power springs 36 may be varied at will to vary the impression forming impact of the types.

The actuator 33 is retracted to normal position by power superior to that of springs 36 and derived from a constantly rotating shaft 49 which is constantly driven clockwise (as the machine is viewed in Figures 1 and 3) by means of an electric motor (not shown) while the machine is in use. Said motor is mounted on the framework 10 and connected to shaft 49 preferably as shown in Crawley Patent 1,503,033. Shaft 49 extends horizontally transversely of the machine to the rear of the actuator, is journaled in the framework 10, and has fixed on its right hand end a ratchet wheel 50.

Opposite the ratchet wheel 50 and adjacent thereto there is journaled in the framework 10 a short crank shaft 51 the axis of which is coaxial with that of shaft 49. A pitman 52 has its rear end pivotally and detachably connected to the wrist of crank shaft 51 and has its forward end pivotally and detachably connected to a lug 53 formed on the cross bar of the actuator 33. The front end of the pitman is connected to lug 53 by a pivot screw 54. At its rear end the pitman is formed with a hook 55 engaged over the wrist of crank shaft 51. A retaining plate 56 has a forked rear end which receives the wrist of the crank shaft and closes the throat of the hook, the front end of said plate being detachably held to the rear section of the pitman 52 by a clamping screw 57 which passes through a downwardly facing slot in said plate. The pitman comprises two sections having adjacent threaded end portions adjustably connected by a turnbuckle 58 for lengthening and shortening of the pitman to vary the normal or retracted position of the actuator 33. Turnbuckle 58 is locked, with the pitman in adjusted condition, by lock nuts 59.

Crank shaft 51 is adapted to be clutched or connected with shaft 49, for a part of a single revolution, through the medium of the ratchet wheel 50 and a pawl 59. Pawl 59 is pivoted substantially midway its ends on a horizontal pivot screw 60 extending transversely of the machine and threaded into an arm or pawl carrier 61 which in turn is fixed on the left hand end of the crank shaft to rotate opposite the right hand face of the ratchet wheel. One arm of the pawl has a nose engageable with the teeth of the ratchet wheel, and a torsion spring 62 coiled about the shank of pivot screw 60 has its opposite ends engaged with this arm of the pawl and with the pawl carrier to normally constantly tend to urge the pawl nose into engagement with the teeth of the ratchet wheel.

Means are provided for manually selecting any desired type bar for actuation and for causing actuation of the selected type bar by the

above described power operated mechanism, which means will now be described.

A part of the framework 10 is formed with a pawl controlling surface 63 which curves downwardly behind and under the periphery of the ratchet wheel concentrically with the coincident axes of the shafts 49 and 51 and extends about said axes for somewhat less than 180 degrees. This surface is so disposed that the arm of the pawl 59 opposite the nose carrying arm of the pawl is normally engaged with said surface adjacent the upper end of said surface to hold the pawl out of engagement with the ratchet. At this point in the revolution of the crank shaft, the wrist thereof is to the rear of the shaft axis and slightly below dead center or a straight line through the centers of said shaft, screw 54 and the shaft wrist, and the free end of the pawl carrying arm 61 is seated upon and held arrested by a spring-cushioned plunger 64. The pawl passes out of engagement with surface 63 and engages the ratchet wheel 50 just before the crank shaft wrist reaches dead center position in front of the shaft axis.

The plunger 64 has two heads and its shank is slidably guided intermediate said heads to move slightly up and down in a bore in the upper portion of a fore and aft rockable arm 65 pivoted at its lower end at 66 on the framework 10. Said plunger is normally held at the upper limit of its motion by a stiff spring 67 adapted to yield momentarily under impact of arm 61 on the upper head of the plunger. A universal release bar 68 extends straightly and horizontally transversely of the machine and is normally located intermediate the cross bar of actuator 33 and the fingers 32 formed on the type action couplers 26. This release bar 68 is formed with rearwardly extending arms fixed to a rock shaft 69 which is disposed at the rear of said bar and journaled at its ends on framework 10. A link 70 pivotally connected at its rear end at 71 to arm 65 near the upper end of the latter is adjustably and pivotally connected at its forward end with rock shaft 69. This latter connection comprises a normally vertically extending part 72 fixed to and extending above and below rock shaft 69, an upstanding arm 73 pivoted at its lower end at 74 to the lower end of part 72 for adjusting movement fore and aft of the machine, a clamping screw 75 which extends through a slot 76 in the arm 73 above pivot 74 and is threaded into the upper portion of part 72 to clamp arm 73 to part 72 in adjusted position, and a pivot screw 95 connecting link 70 to arm 73. A return spring 77 connected to release bar 68 and the framework 10 normally returns the release bar 68 and arm 65 to position the plunger 64 in pawl carrier arresting position, said spring normally urging a stop lug 78 formed on the upper end of part 72, forward against a stop pad 79 held to framework 10.

The release bar 68 is rockable upward and rearward by any coupler finger 32 to disengage the plunger 64 from the pawl carrier by upward swinging of any one of the couplers 26 about its pivot 25 into a position placing coupler shoulder 31 in front of the cross bar of actuator 33 for forward driving of the actuated coupler by the actuator.

The couplers are selectively operable by the type keys 80 of the keyboard of the machine, which keys are arranged as usual in four stepped banks or rows and are carried on the forward ends of two-arm key levers 81 which extend

fore and aft of the machine. The key levers are pivoted on different ones of four horizontal and fore-and-aft spaced pivot rods 82 which extend transversely of the machine, the key levers for the forward or lowest bank being pivoted on the foremost rod, and those for respective ones of the other banks being pivoted in progressive order from bank to bank on the remaining rods in the known manner for substantially equal upward movement of the rear ends of the levers for a given key dip. Return springs 83 connected to framework 10 and the rear ends of the key levers normally hold the forward arms of the key levers up against the usual key lever stop pad 84 carried by a key lever guide comb 96 held to framework 10. The rear arms of the key levers are guided in the slots of a guide comb 85 held to framework 10 below coupler rest 28, and said key lever arms are engageable with a stop 86 held to said comb to limit upward movement of said rear arms of the key levers.

At the rear of comb 85 each key lever has pivoted thereto at 87 a normally upstanding two-arm thrust lever 88, the lower arm of which is connected by one of a series of rearwardly extending springs 89 to its associated key lever 81 to normally hold the upper arm of the thrust lever forward against a cushioning stop pad or strip 90 fixed to a thrust lever guide comb 93 which is held to frame 10 and extends horizontally and straightly across the machine. Each thrust lever 88 is formed at its upper end with a short lateral extension or lug 91 disposed slightly below and engageable with but a single one of the couplers 26.

Upon depression and release of any type key, the following operation takes place:

The thrust lever 88 connected with the key lever whose key is depressed rocks the associated coupler 26 upwardly and the coupler finger 32 rocks the release bar 68 upwardly to carry plunger 64 rearward out of engagement with pawl carrier 61 by the time coupler shoulder 31 is positioned in front of the cross-bar of actuator 33. Springs 36 then instantly pull the actuator forward to the limit of its forward stroke driving the key-actuated coupler forward, at which time the sub-lever finger 22^a of the sub-lever connected with the actuated type bar comes into contact with the associated cushioning and repulsing spring 24 with the type of the actuated type bar spaced appreciably from the paper backed by platen 11, after which the type bar is carried to its printing limit by momentum and then quickly started on its return stroke by the repulsing spring. The printing stroke of the type bar carries the coupler forward out of contact with the thrust lever 88 and the fully advanced actuator and the release bar and the coupler drops instantly on the coupler rest, releasing the release bar 68 and plunger 64 which move back instantly to normal position under the influence of spring 77.

On the return stroke of the actuated type bar by its associated springs 24 and 21, the coupler will slide under the release bar. If the key is still depressed at this time, the coupler finger will rock the upper arm of the thrust lever rearward below the returned release bar and this arm will snap forward under said finger after the key is released. If the key is quickly released, the coupler finger will slide rearward between the release bar and the thrust lever. Just before the actuator 33 is fully advanced by springs 36, the pawl

59 passes off the lower end of surface 63 and its nose snaps into engagement with a tooth of constantly rotating ratchet 50 which thereupon drives the crank shaft 51 positively through the remaining somewhat more than one-half of a single revolution until the pawl is kicked out of engagement with the ratchet wheel by coming into contact with the upper end of surface 63. As the pawl is disengaged from the ratchet wheel, its carrier arm 61 impacts the restored plunger 64 and is brought to rest after a single revolution of the crank shaft. The actuator is thus retracted by the motor driven shaft against the resistance of springs 36. No matter how long a type key may be held depressed, the associated type bar will be actuated to print and return only once.

We claim:

1. In a typewriting machine of the kind having a main framework, a platen carriage mounted on said framework, a platen on the carriage, and an actuate system of type bars pivoted to swing upward and rearward to the platen to print and bodily shiftable up and down as a unit in the framework for upper and lower case printing, key controlled power actuated means for selectively actuating the type bars comprising, in combination, a system of upstanding sub-levers of the first order, a system of links all of equal length extending fore and aft of the machine with their front ends pivoted to the type bars above and forward of the pivots of the respective type bars and their rear ends pivoted to the upper ends of the sub-levers, the link pivots and type bar pivots lying in concentric arcs which lie in parallel planes, the sub-levers being fulcrumed in the framework to swing fore and aft of the machine about fixed axes with their lower ends in alignment transversely of the machine and their axes so located that each lever has upper and lower arms of substantially equal effective length, a series of identical couplers extending fore and aft of the machine and normally located in a straight horizontal row which extends transversely of the machine, said couplers pivoted at their forward ends to the lower ends of the sub-levers to swing vertically and their pivots being normally coaxial, normally inactive power actuated means including a universal coupler actuator movable first forwardly and then backwardly in the framework from a normal idle position during a single cycle of operation of the power actuated means, a set of type keys, one for each coupler, and means operable by each type key to swing its associated coupler upward into the path of said actuator, said power actuated means being releasable for a single cycle of operation by upward swinging of either one of the couplers.

2. In a typewriting machine of the kind having a main framework, a platen carriage mounted on said framework, a platen on the carriage, and an actuate system of type bars pivoted to swing upward and rearward to the platen to print and bodily shiftable up and down as a unit in the framework for upper and lower case printing, key controlled power actuated means for advancing the actuator a limited distance and retracting it to normal position, means carried by each key lever for swinging a different one of the couplers upward into the path of forward movement of the actuator, spring-return means for holding the power means against actuator vibrating operation releasable by upward swinging of either coupler and freed from contact by a lifted coupler during the printing stroke of the associated type bar, and a straight horizontal row of upstanding leaf springs mounted on the framework forward of the lower arms of the sub-levers, the lower arms of each sub-lever having a pendent fore and aft adjustable finger engageable with the adjacent spring before the associated type bar reaches the platen on a printing stroke thereof, the limit of the forward stroke of the actuator being such that it cannot positively drive the type bar to the printing point.

3. In a typewriting machine of the kind having a main framework, a platen carriage mounted on said framework, a platen on the carriage, and an

actuate system of type bars pivoted to swing upward and rearward to the platen to print and bodily shiftable up and down as a unit in the framework for upper and lower case printing, key controlled power actuated means for selectively actuating the type bars comprising, in combination, a system of upstanding sub-levers of the first order, a system of links all of equal length extending fore and aft of the machine with their front ends pivoted to the type bars above and forward of the pivots of the respective type bars and their rear ends pivoted to the upper ends of the sub-levers, the link pivots and type bar pivots lying in concentric arcs which lie in parallel planes, the sub-levers being fulcrumed in the framework to swing fore and aft of the machine about fixed axes with their lower ends in alignment transversely of the machine and their axes so located that each lever has upper and lower arms of substantially equal effective length, a series of identical couplers extending fore and aft of the machine and normally located in a straight horizontal row which extends transversely of the machine, said couplers pivoted at their forward ends to the lower ends of the sub-levers to swing vertically and their pivots being normally coaxial, normally inactive power actuated means including a universal coupler actuator movable first forwardly and then backwardly in the framework from a normal idle position during a single cycle of operation of the power actuated means, a set of type keys, one for each coupler, and means operable by each type key to swing its associated coupler upward into the path of said actuator, said power actuated means being releasable for a single cycle of operation by upward swinging of either one of the couplers.

4. In a typewriting machine of the kind having a main framework, a platen carriage mounted on said framework, a platen on the carriage, and an actuate system of type bars pivoted to swing upward and rearward to the platen to print and bodily shiftable up and down as a unit in the framework for upper and lower case printing, key controlled power actuated means for selectively actuating the type bars comprising, in combination, a system of upstanding sub-levers of the first order, a system of links all of equal length extending fore and aft of the machine with their front ends pivoted to the type bars above and forward of the pivots of the respective type bars and their rear ends pivoted to the upper ends of the sub-levers, the link pivots and type bar pivots lying in concentric arcs which lie in parallel planes, the sub-levers being fulcrumed in the framework to swing fore and aft of the machine about fixed axes with their lower ends in alignment transversely of the machine and their axes so located that each lever has upper and lower arms of substantially equal effective length, a series of identical couplers extending fore and aft of the machine and normally located in a straight horizontal row which extends transversely of the machine, said couplers pivoted at their forward ends to the lower ends of the sub-levers to swing vertically and their pivots being normally coaxial, normally inactive power actuated means including a normally retracted forwardly movable coupler actuator mounted in the rear part of the framework and releasable by either of the couplers upon upward swinging of the coupler into the path of the actuator for a single forward and return movement, a type key

for each coupler, means operable by depression of each type key to swing its associated coupler upward into the path of forward movement of the actuator for forward driving of the coupler by the actuator to impart a printing stroke to the associated type bar, the length of stroke of the actuator being such that the forward limit thereof is reached before the type bar reaches the platen, and repulser springs in the framework each engageable by a different one of the sub-levers during the final portion of the printing stroke of a type bar connected with the active sub-lever.

4. In a typewriting machine, a main framework, a platen, type carriers movable to and from the platen, upstanding fore and aft swinging sub-levers of the first order fulcrumed in the framework and each connected at its upper end with a different type carrier to move the latter to the platen upon forward movement of the lower arm of the sub-lever and all arranged with their lower ends normally in alignment transversely of the machine, fore and aft extending couplers normally aligned transversely of the machine and pivoted at their forward ends to the lower ends of the sub-levers for up and down swinging movement, a stationary horizontal coupler rest in the framework extending transversely of the machine and upon which the couplers are normally seated, tension springs anchored to the framework and each anchored to a different one of the couplers to normally urge the coupler and the sub-lever and type carrier connected therewith to normal idle position, fore and aft extending type key levers of the first order fulcrumed in the framework to rock up and down and having their rear ends extending under the coupler rest, normally upstanding coupler lifting levers of the first order each fulcrumed on the rear portion of a different one of the type key levers, springs connecting the lower arms of the lifting levers to the respective key levers to urge the upper arms of the lifting levers forwardly, a horizontal stop on the framework extending transversely of the machine and against which the upper arms of the coupler lifting levers are normally held upright by their springs with the upper ends of said levers beneath the respective couplers below and in rear of the coupler rest, each coupler having a rearwardly facing shoulder extending downward from its upper edge and a rearward extension below said shoulder, a normally stationary forwardly and rearwardly movable universal type carrier actuator normally overhanging said coupler extensions, each coupler being rockable upward by its lifter to present its rearwardly facing shoulder in the path of forward movement of the actuator for forward driving of the coupler by the actuator to impart a printing stroke to the associated type carrier, and power means releasable by lifting movement of either one of the couplers to impart a single forward and return movement to the actuator, said actuator having a straight horizontal bar extending transversely of the machine for driving engagement with the coupler shoulders and normally disposed above and in rear of said shoulders, said power means including means for so limiting the forward movement of said actuator bar that the couplers move forward out of contact with said bar and drop to the coupler rest during the final portion of the printing strokes of their associated type carriers.

5. In a typewriting machine, a main framework,

a type bar actuating ball having a straight cross-bar extending horizontally transversely of the machine and pendent side arms adjacent opposite sides of the machine fulcrumed on the framework at their lower ends to rock about a horizontal axis extending transversely of the machine, a horizontal rock shaft extending transversely of the machine forward of the actuator and journaled on the framework and having two pendent rock arms fixed thereto adjacent opposite sides of the machine, a pair of constantly tensioned pull springs anchored at their rear ends to the side arms of the actuator and at their front ends to the lower ends of said rock arms, a rearwardly extending rock arm fixed on said rock shaft, a roll journaled on the rear end of said rearwardly extending rock arm to rotate about an axis parallel to that of said shaft, a conversely rotative shaft journaled on the framework and extending horizontally transversely of the machine above said roll, a plate cam fixed on said conversely rotative shaft and having an eccentric peripheral edge provided with spaced notches engageable by said roll, a handle fixed on said conversely rotative shaft for rotating the shaft and cam, a pair of spaced projections on said cam engageable with said roll to limit rotation of the cam in both directions, a series of type carriers, type keys, individual spring returned driving means for the type carriers each settable by depression of a different one of the type keys for actuation by the actuator when the latter is pulled forward by said pull springs to cause a printing stroke of a selected type carrier, a fore and aft extending pitman connected at its forward end to the actuator, a crank shaft journaled on the framework to rotate about a horizontal axis extending transversely of the machine and having the rear end of the pitman connected to the wrist thereof, latch means normally holding said crank shaft with the actuator retracted and controlled by the setting action of either of said spring returned driving means to release the crank shaft for rotation through a single revolution only whether or not said key is released, and automatic power means for retracting the actuator to latched position through the medium of said crank shaft and pitman.

6. A typewriting machine, as claimed in claim 5, wherein the pitman comprises two threaded sections, a turnbuckle connecting said sections for adjustment of the length of the pitman, and a pair of turnbuckle-locking nuts threaded on the respective pitman sections against opposite ends of the turnbuckle.

7. In a typewriting machine, type carriers, a rockably mounted actuator for the type carriers, operating trains connected to the respective type carriers and each including a coupler settable for actuation by the actuator to impart a printed stroke to its connected type carrier, spring means for moving the actuator in a direction to impart a printing stroke to a type carrier, a crank, a pitman connected to the crank and actuator for limiting the working stroke of the actuator and retracting the actuator, said pitman including means for adjusting the effective length thereof, latch means for locking the crank in a position to hold the actuator retracted, a rockably mounted and spring-retracted release bar adjacent the actuator operable by setting movement of any coupler to release said latch means for a single revolution of the crank, a return stop for the release bar, a link connection between said release bar and latch means including provision for vary-

ing the effective length of said link connection, and power means for automatically and positively driving said crank during a portion of each revolution to retract the actuator.

8. In a typewriting machine having a rockable type bar actuator, a system of type actions selectively settable for actuation to printing position by a driving impulse from the actuator, and normally ineffective power means for automatically retracting the actuator to a normal idle position, the combination of a bellcrank rockable about an axis parallel to that of the actuator, a constantly tensioned pull spring connected at its ends to said actuator and to one arm of the bellcrank to

exert a type bar driving effort on the actuator, a roller journaled on the other arm of said bellcrank, a cam rockable about an axis parallel to that of the bellcrank and located substantially in the vertical plane of the roller, and a handle for conversely rotating the cam, said cam having an eccentric peripheral edge portion provided with a series of notches in which said roller is selectively seatable and also being formed with projections at the ends of said edge portion engageable with the roller to limit rotation of the cam.

HENRY A. AVERY.
CHARLES WALKER.
